UNITED STATES PATENT OFFICE.

WALTER J. STANGE AND LEWIS M. BANNAN, OF SAN FRANCISCO, CALIFORNIA,
ASSIGNORS OF ONE-THIRD TO ROCKWELL L. STONE, OF SAN FRANCISCO, CALIFORNIA.

MOTION-PICTURE APPARATUS.

1,261,865.

Specification of Letters Patent.

Patented Apr. 9, 1918.

Application filed October 11, 1915. Serial No. 55,175.

To all whom it may concern:

Be it known that we, WALTER J. STANGE and LEWIS M. BANNAN, citizens of the United States, residing at the city and county of San Francisco, State of California, (whose post-office addresses are, respectively, #37 Montgomery street and #2130 Pierce street, they having assigned one-third interest to Rockwell L. Stone, of the same place,) have invented new and useful Improvements in Motion-Picture Apparatus, and more particularly the method of and machines for printing motion-picture films, of which the following is a specification.

15 Among the objects of this invention are:

To provide means for controlling the quantity of light according to the density of the film negative under exposure;

To provide a light control mechanism adjustable to use with the conventional form of lantern and film feed mechanism as at present combined in motion picture projecting and printing machines.

In the drawings:

25 Figure 1 is a side elevation of a printing machine constructed and arranged in accordance with this invention.

Fig. 2 is an end elevation of the same partially in cross section on the line 2—2.

30 Fig. 3 is a fragmentary enlarged detail of the screen mechanism.

Fig. 4 is a fragmentary detail of the lower end of the lock dog engaging the screen lever.

35 Fig. 5 is a diagrammatic detail in cross section showing the interrelation of parts of the source of light, the interposed screen, and the aperture plate of the printing machine.

40 Fig. 6 is an enlarged detail of the suction bellows of the pneumatic mechanism.

Fig. 7 is a fragmentary detail partially in cross section, of the tracker-board mechanism.

45 Fig. 8 is a detail top view of the tracker-board.

Fig. 9 is a diagrammatic plan view of a section of perforated negative passing over the tracker-board, in engagement with the

50 sprockets of the feed mechanism.

Fig. 10 is a similar view of the same showing a modified form of negative film.

55 Fig. 11 is a similar view of the same showing a modified tracker-board and feed

mechanism adapted to feed the negative and the pneumatic feed strip in unison.

Other objects and advantages will appear as the description progresses. In the five sheets of drawings accompanying and forming part of the present specification, to which like reference characters have been applied, a simple form of putting this invention into practice is shown. We do not wish to be understood as confining this invention to the disclosures made in said drawings and description, as many variations may be introduced within the spirit of this invention, as defined in the claims succeeding the said description.

70 The production of motion pictures includes three primary steps:

Photographing the action. This first step is often taken in constantly varying conditions of light, involving changing of focus and light stops. The completed negative may comprise short lengths of film taken at different times of day, during different atmospheric conditions, under stress of excitement, affecting the over or under exposure of the film, due to the judgment or inadvertence of the camera operator.

75 These various conditions result in a negative made up of short lengths, that when developed and pasted together in proper sequence, produce a continuous film negative, the various sections of which will vary in density, from extremely transparent underexposed or over developed sections, to extremely dense over exposed or under developed portions.

80 The second step in the process is to superimpose the negative over a sensitized film and photographically transfer the impression from the negative to the film, which when properly developed become a "positive."

85 The final step is to feed the positive through the projecting machine, which discloses the action registered on the film, on a suitable screen, in the well known manner.

90 It is obvious that a positive showing all the imperfections of lighting, described as present on the original negative, would seriously interfere with the quality of the screen production. To overcome this disadvantage it has been the practice to "time" the exposure during the printing process, giving more time to the dense portions of the negative in transit through the printing

70

80

105

110

machine, and less time to the more transparent portions of the film. These variations in producing each positive reproduction of the negative renders the process 5 laborious and expensive, and with the closest attention, it is practically impossible to produce duplicate positives of the same light values throughout their lengths. By the means and methods involved in this invention, it is possible for the expert film-printer to so mark the original negative, according to this judgment of light values, that every positive produced from that negative will be exact duplicates in the 10 light values throughout their lengths, producing on the screen uniform and consistent lighting, in accordance with the subject being produced; reproducing the judgment of an expert in such matters, permanently impressed upon the original negative, so as 15 to be mechanically reproduced at the minimum of cost and the minimum attention of skilled printers.

In the practice of this invention as stated, 20 the feed mechanism of an ordinary projecting machine may be used, and will herein-after be called the printing machine. The light from the lantern is focused through a condenser onto the aperture plate of the printing machine, behind which the super-imposed negative and film are intermittently fed in the usual manner. The intensity of the light being a given quantity, and for 25 mechanical reasons not easily controlled at its source according to a definite scale, the expedient is adopted of interposing screen units of known density, between the source of light and the negative. These screen units are automatically controlled individually or in groups, by perforations or other 30 means registered on the negative.

In detail the construction illustrated in the drawings include the lantern 1, inclosing some source of light production, preferably 35 electric. The beam of light passes through a condenser fixed in the tube 2 of the lantern. Opposite the lantern and preferably mounted on the same base 3, is the printing mechanism, including the aperture plate 4, 40 mounted upon the frame 5 of the printing mechanism. The aperture plate is set in focal line with the condenser in the tube 2 of the lantern. The printing mechanism includes the film feeding mechanism above and 45 below the aperture plate, comprising the sprockets 6 and 7 synchronously operated, and engaging the perforations in the edge of the film negative and positive. It is the function of this feed mechanism to maintain 50 a length of slack film between them. This film slack is engaged by the sprocket 8 synchronized with the feed described, but controlled by a cam and pin, or a "Geneva" movement 9, indicated in dotted lines be- 55 hind the sprocket 8; whereby the intermit-

tent feed mechanism brings each exposure area or negative unit to a dead stop, and framed in the aperture plate opening, in its passage through the printing machine. This intermittent feed mechanism varies in different makes of machines, and applicants do not wish to be understood as confining their invention to any particular mechanism designed to perform that particular function, in the operation of this invention that may 70 be combined with any of the many forms having different characteristics.

The printing machine is operated by the motor 10, the shaft 11 of which is provided with a driving pulley engaging the belt 12 80 driving the pulley 13 fixed to the counter shaft 14, having a smaller pulley fixed thereon engaging the belt 15, driving the larger pulley 16 fixed to the driven shaft 17 of the feed mechanism. This train of belts and 85 pulleys acting as a reduction gear between the motor shaft 11 and the feed shaft 17, maintaining the proper ratio of speed. The negative film X and the positive film Y are 90 unwound from their respective reels X¹ and Y¹, through the printing machine, and onto their respective reels X² and Y². The positive film Y, properly sensitized in the usual manner, is brought into contact with the negative X, both of which have registering 95 perforations X³ and Y³ engaging the sprockets 6, 7 and 8 of the feed mechanism; whereby the light projected through the negative X registers a photographic impression of itself on the film Y, in traversing the opening in the aperture plate. It is necessary to 100 protect the film Y against exposure to light, except that projected through the aperture plate. The film is therefore contained in the light proof film shields or boxes Y⁴, Y⁵ 105 and the apertures are also preferably enclosed to exclude light, no such means being shown in the drawings, to avoid confusion, such elements being understood as a part of the printing machine.

Attention is directed to the section of the film X, illustrated best in Fig. 9 through which punctures 18, 19, 20 and 21 are made without removing any of the material thereof, leaving a lip projecting beyond the plane 110 of the film but providing an opening through which air may be drawn by the pneumatic mechanism herein-after described. These various punctures are illustrated as occurring frequently on the film for better description; 115 as a matter of fact they may not occur oftener than once in fifty feet of film, more or less according to variations in the transparency of the film. These punctures coincide with the openings 24, 25, 26 and 27 of the 120 tracker board 30 (see Figs. 7 and 8). To permit the depression of these tongues the tracker board openings are countersunk as 125 at 31.

The openings in the tracker board are con- 130

5 nected by the flexible tubes 32, 33, 34 and 35 with the collapsible pouches 36, 37, 38 and 39. These various pouches are connected with a manifold vacuum chamber 42, connected by the tube 43, to the exhaust pump driven by the motor 10, maintaining a constant suction on all of the pouches, until one of the punctures in the film passes over one of the openings in the tracker board; in this 10 event the tongue of the puncture is sucked downward admitting air to its respective pouch that immediately collapses. The bellows 45, maintained in the distended position by the spring 46, is connected with the 15 vacuum chamber 42 and has sufficient capacity to permit the sudden collapsing and exhaustion of all of the pouches therethrough. The vibrating tops 47, 48, 49 and 50 of the pouches are respectively connected 20 by the cords 52, 53, 54 and 55 to their respective screen levers 57, 58, 59 and 60 all fulcrumed on the pin 62, fixed in the side frames 63 secured on the base 3.

These screen levers project on the opposite 25 side of the fulcrum 62, and are connected on one side of the operating pouches by the cords as described. The ends of the screen levers are provided with heads having an incline planes 64 approaching the notch 65. 30 The collapsing of the pouch connected to a lever, pulls the lever downward to the horizontal position illustrated in dotted lines in Fig. 2. At the completion of this downward movement, the dog 66 pivoted at 67, on the 35 bracket 68 mounted on the support 63, rides up the incline 64, and the lug 69 lodges in the notch 65, locking the lever in the horizontal position. The dog 66 is pulled backward by the tension of the spring 70, having 40 its opposite end attached to the bracket 68. The opposite end 71 of the screen lever is provided with a frame 72, in which the screen 73 is fixed. When the screen lever is thrown into the operative or horizontal position by 45 the means previously described, the screen 73 is brought into coincidence with the aperture 74 in the aperture plate 4, interposing the screen in the beam of light emanating from the lantern 1, focused on the aperture as described. In the present instance five screens 50 are shown 73, 73^a, 73^b, 73^c, and 75. See Fig. 5. The first four are of various degrees of opacity, accomplished by the double thickness in the screen 73^a, the triple thickness of 55 73^b, and the quadruple thickness of 73^c, all of which may be interposed singly, or in multiples, or simultaneously, to reduce the intensity of the light falling upon the aperture. The last screen 75 is preferably of 60 metal or some absolutely opaque substance, and is intended to be operated by the pneumatic mechanism if the film breaks, or the feeding mechanism stops, to prevent the light burning the films.

65 The negative film X (see Fig. 7), passes

over the aperture plate 30, around the roller 77, over the roller 78, and meets the film Y, both passing through the feed mechanism in unison, as hereinbefore described. From the lower feed sprocket 7 the negative passes 70 onto its takeup reel X². These various reels X¹, X², Y¹, and Y² are frictionally driven in conjunction with the feed mechanism in the usual manner to pay off and take up their respective lengths of film. The proper contact 75 between the negative and the tracker board 30, is maintained by the endless belt 78, interposed between the negative and the rollers 76 and 70, to exert sufficient pressure on the negative to insure its constant contact 80 with the tracker board, the slack of the belt being taken up by the roller 80. These various rollers are mounted in the spider 81, fixed to the bracket 82 extending outward from the reel box. Some such contact insuring 85 means is desirable, for the reason that the lifting of the film from the tracker board would admit air to the holes therein, operating the pouches, independent of the predetermined perforations in the negative, but 90 we do not wish to be understood as confining this invention to the particular means shown for this purpose, as rollers, or other means may be provided for putting tension upon the film in its passage over the tracker board. 95 The belt 78 as shown is preferred at this time, because traveling with the negative it minimizes the wear thereon, and may be made of fabric or other pervious material through which air may be drawn through the perforations in the negative. Inasmuch as all 100 of the pneumatic screen operating mechanisms are identical, except as to the quality of their respective screens, the following description of the operation of the device will 105 be confined in detail to one screen, it being obvious that the same mechanical effects take place in the various screen mechanisms.

Very dark portions of the negative require 110 the maximum quantity of light to produce the required photographic effect on the positive; such dark portions of the film are not perforated, consequently will not act upon the pneumatic screen control. Portions of the film less opaque than the dark portions 115 thus described, if subjected to the maximum amount of light during the given time of exposure, would print too dark upon the positive in contact therewith, presuming such a portion of the negative to be represented 120 by the perforation 8.

Referring to Fig. 9, the perforations 18 indicates by its transverse location that this is a dense or dark portion of the negative. When this perforation passes over the hole 125 25 in the tracker board, that is connected by the tube 3 with the pneumatic 36, the latter is collapsed by the admission of air therein through the perforation 18. The collapse of the pneumatic 36, through its connecting 130

cord, pulls down and locks the screen lever 71 in the horizontal position as described, which interposes the screen 73 between the light and the negative, which reduces to the 5 degree of opacity of the screen, the light striking the negative.

Portions of the film less dense or dark than those described, call for a greater modification or lessening of the quantity of light 10 projected through the negative, in order to maintain uniform lighting in the result and positives. The perforations 19, 20 and 21, represent by their transverse locations, graduations in the relative transparency of the 15 negative. Very transparent portions would be perforated as at 21 such portions calling for the interposition of the density of screen as in 73^a, which would be thrown into position when the perforation 21 passes over the 20 hole 29 in the tracker board. The perforations intermediately located in the film, control the intermediate variations of screen, thrown into position by the passage of such perforations over their respective holes in 25 the tracker board. Any multiple of the screens may be thrown into operative position by grouping the perforations in the film, for instance in Fig. 9 a group of perforations controlling screens 73, 73^a, 73^b, 73^c 30 are arranged in transverse alignment to simultaneously uncover the holes in the tracker board to interpose in the beam of light all of the screens mentioned, giving the total maximum reduction of the light. 35 Other combinations of screen control are sufficiently obvious.

When it is desirable to remove one or all of the screens interposed in the light as described, the film is perforated as at 83, un- 40 covering the hole 84 in the tracker board, that controls the pouch 85 connected by the cord 86 to the end 87 of the bell crank lever 88 pivoted at 89. The lever 88 is duplicated on opposite sides of the frame and 45 connected by the cross bar 90, lying behind the bank of dogs 66. The collapsing of the pneumatic 85 through the connected mechanism, forces the cross bar 90 forward, dislodging the dogs 66 from the notches 65, 50 permitting all of the screens in the operative position, to drop to the inoperative position illustrated in Fig. 3. The succeeding portions of the negative are perforated in accordance with their transparency as de- 55 scribed.

The hole 91 in the tracker board controls the pouch 92, that is directly connected to the bar 93 of the electric switch 94, interposed in the power mains 95 supplying the 60 motor 10 with power; the uncovering of the hole 90 by the perforation 96, opens this switch and stops the motor. The perforation 97 controls the pouch 98, that operates the screen 75, interposing the opaque screen 65 in the beam of light, stopping the process

of printing through the negative. When these perforations 96 and 97 occur in unison the whole of the printing operation is stopped. The source of power to the light may be on the same mains 95 that supply 70 the motor, the light would be extinguished simultaneously with the stopping of the motor. It is obvious also that a break in the film would simultaneously uncover all of the holes in the tracker board, shutting down 75 the operation of the whole mechanism that is controlled through the medium of the tracker board.

Perforating the film in the manner de- 80 scribed does not materially damage it, but if for any reason it is undesirable thus to mark it, the modified film illustrated in Fig. 10 may be used, as the negative. This consists of the photographic film Z having a marginal portion Z¹ through which the con- 85 trol punctures Z², Z³, Z⁴, Z⁵, Z⁶ and Z⁷ are made to operate the pneumatics as described.

A further modification of the film control is illustrated in Fig. 11, in which the feed sprockets are duplicated and a control strip 90 property punctured is passed over the tracker board in unison with the negative passing through the printing machine, to control the pneumatics in accordance with the nature of the portion of the negative coinciding with 95 the perforated portion of said strip.

Having thus described this invention what we claim and desire to secure by Letters Patent is:

1. A photographic printing machine in- 100 cluding a plurality of screens; pneumatically controlled levers for automatically interposing said plurality of screens between the source of light and the negative ex- 105 posed thereto, said levers operated accord- ing to the transparency of said negative.

2. A photographic printing machine in- 110 cluding a plurality of screens; pneumatically controlled levers for automatically interposing and withdrawing screens between the source of light and the negative ex- 115 posed thereto, said levers operated accord- ing to mechanical markings on the negative.

3. A photographic printing machine in- 115 cluding a source of light; a plurality of screens, means for controlling the intensity of said light by interposing said plurality of screens in series including means governed by passing air through suitably located ap- 120 pertures in a negative exposed thereto.

4. A photographic printing machine in- 125 cluding a source of light; a negative; a series of screens; pneumatic means for inter- posing screens of said series between said light and said negative and including means governed by passing air through suitably placed apertures in said negative for operating said screens.

5. A photographic printing machine in- 130

cluding a source of light; a series of screens of different densities; a tracker board; and means for independently and collectively operating said screens according to characteristic markings on a film passing said tracker board.

6. A photographic printing device including a source of light, a tracker board having pneumatics attached thereto; a series of 10 interposed screens connected with said pneumatics; and a perforated film adapted to pass over said tracker board and coöperate with said pneumatics to cause said screens to operate.

15 7. A photographic printing machine including a source of light; a plurality of pivoted levers; a plurality of screens on said levers; an aperture plate; pneumatics; a tracker board connected with said pneumatics; pneumatically controlled means for interposing said screens between said source of light and said aperture plate; means for raising and locking said levers and means for releasing said levers according to characteristic markings on a film passing said 25 tracker board.

8. A photographic printing machine including a source of light and a negative exposure mechanism; a series of screens; means for interposing said series of screens 30 between said source of light and the negative exposure mechanism; and means for controlling said screen operating mechanism according to characteristic markings on a portion of the film negative exposed to the 35 source of light.

9. A photographic printing machine including a source of light; a series of independently operated screens and means for interposing a plurality of said screens before 40 said source of light according to characteristic marking on a film passing said source of light.

In testimony whereof, we have hereunto set our hands this 18th day of September 45 1915.
